INKING DEVICE

David Hoppenstand, Pittsburgh, Pa., assignor to
 Hopkan Rivet Company, Inc., Pittsburgh, Pa.,
 a corporation of Pennsylvania

Application February 11, 1935, Serial No. 6,000

6 Claims. (Cl. 197—171)

My invention relates to inking devices and, in particular, to a device for inking the printing ribbon of typewriting and similar machines.

I have observed that printing ribbons are rendered useless by the removal of most of the ink with which they are impregnated in manufacture, or by drying out, in use, long before the fabric of the ribbon has worn materially. An object of my invention, therefore, is to provide means for renewing the ink content of the ribbon during use. In accordance with my invention, I provide an ink container adapted to be carried on the housing which usually encloses the ribbon reel of a typewriting or other similar machine, a roller adapted to receive ink from the container and deliver it to the ribbon, and means for forcing the ink from the container onto the roller.

The manner in which I realize the foregoing and other objects which will become apparent hereinafter, will be explained in connection with the accompanying drawing illustrating a preferred embodiment of the invention, the novel features of which will be specifically pointed out in the appended claims.

25 In the drawings,

Fig. 1 is a diagrammatic plan view showing the invention applied to one of the usual ribbon reel housings of the ordinary typewriter;

Fig. 2 is a side elevation of the device;

30 Fig. 3 is a plan view thereof;

Fig. 4 is a sectional view along the line IV—IV of Fig. 3;

Fig. 5 is a sectional view along the line V—V of Fig. 4;

35 Fig. 6 is a sectional view along the line VI—VI of Fig. 2;

Fig. 7 is a view similar to Fig. 6 with certain parts omitted for the sake of clearness, and

40 Fig. 8 is a sectional view similar to Fig. 4 showing a portion only of the device, to enlarged scale.

Referring now in detail to the drawing, the invention comprises an ink container, preferably in the form of a cylinder 10. The side wall of the cylinder 10 is slit at 11 to provide an outlet for the ink. A protuberance 12 from the base 13 of the cylinder, adjacent the opening 11, has a pin 14 threaded thereinto. A roller 15 is journaled on the pin and the latter also serves to retain in position, a cup 16 carried on the protuberance 12 and overlying the pin and roller, as well as the slit. The sides of the cup have slots 17 for guiding the ribbon into contact with the roller, as indicated in Figs. 1 and 5.

55 I prefer to supply ink to the ribbon only when

it is moving toward the printing position, and not when it is being wound up on the reel after passing such position, although, if desired, one of the devices may be attached by means to be described shortly to each of the reel housings, so that the ribbon will be inked when moving in either direction. To this end the bottom of the roller 15 is provided with a cam recess 18 adapted to cooperate with a stop pin 19 projecting upwardly through the protuberance 12 and a notch 10 in the bottom of the cup 16. By this means, the roller is permitted to turn in one direction by reason of the frictional engagement of the ribbon therewith, but is prevented from turning in the opposite direction.

The upper end of the cylinder 10 is closed by a sleeve 20 threaded thereinto and extending downwardly thereof, with a plug 22 screwed therein. A felt strip 23 extends around the sleeve 20 and substantially fills the space between the sleeve and the cylinder. The sleeve has a flange 24 which serves to hold in place a ring 25 having a depending clip 26, by which the device may be attached to a ribbon reel housing as indicated at 27 in Fig. 1. In the latter, the reel is shown at 28 and its actuating spindle at 29. The housing carries a guide pulley 30 about which the ribbon is trained onto the reel.

A piston 31 is slidable in the cylinder 10 and has projections 32 adapted to slide in grooves in 30 the cylinder wall, indicated at 33. Rotation of the piston in the cylinder is thus prevented.

A feed screw 34 is journaled in the plug 22 and is threaded through the piston. A knurled knob 35 is secured to the upper end of the screw which also carries a pointer 36 adapted to cooperate with scale markings on the periphery of the plug, to indicate the position of the piston on the screw. The edge of the plug is also knurled to facilitate removal thereof for the purpose of filling the 40 cylinder with ink.

Holes 37 in the sleeve 20 permit the ink to flow from the container 10 into the felt 23 through which it moves by capillary attraction to the point of removal, viz., the point at which the 45 roller 15 engages the felt through the slot or opening 11.

It will be apparent from the foregoing description that the invention provides a simple, inexpensive, compact yet effective device for re-inking typewriter or other printing ribbons in use. The mode of operation will be self evident. The container is filled with ink by removal of the plug and piston. On replacement of the plug and piston and advancement of the latter by turning 55

the feed screw, the ink which is of a somewhat thick or pasty consistency, is forced into the felt through the holes 37. As before stated, the felt delivers the ink by capillary attraction to the point where it is removed therefrom by the roller 15. The pointer 36 always indicates the amount of ink remaining in the container.

5 The pointer 36 will easily serve to show the position of the piston if the number of graduations agrees with the number of turns of the screw required fully to advance the piston. After 10 each turn of the screw the pointer can be stopped on the next succeeding graduation, thus showing the position to which the piston has been advanced.

15 The device requires no special tools for installation, nor, indeed, any changes whatever in the construction of the machine to which it is attached, since it is merely secured in place by the grip exerted by the clip 26. The cam surface 18 on the bottom of the roller 15 causes the latter to reciprocate axially as it rotates, thereby more effectively distributing the ink from the felt onto the ribbon.

20 25 While I have illustrated and described herein but one present preferred embodiment of the invention, it will be obvious that many changes therein may be made without departing from the scope of the appended claims.

30 I claim:

1. A web inking device comprising a cylinder, a sleeve extending thereinto, a piston reciprocable in said sleeve, an opening in the wall of the cylinder, a roller journaled for rotation thereadjacent, 35 guides for directing the web around the roller, a fibrous filling between the sleeve and cylinder

adapted to be engaged by the roller through said opening, and openings in the sleeve for feeding ink therefrom to said filling.

2. A web inking device comprising an inking roller, a reservoir disposed adjacent thereto adapted to feed ink to the roller for delivery to a web moving therewith, and means to prevent reverse rotation of the roller on reversal of said web.

3. In a web-inking device, a roller adapted to be engaged by the web, means for supplying ink to the roller, and means for moving the roller axially as it rotates.

4. The apparatus of claim 3 characterized by said last-mentioned means effecting reciprocation of the roller.

5. A ribbon inking device comprising a cylinder, a roller journaled adjacent thereto adapted to be engaged by the ribbon, a sleeve in the cylinder, wick means between the sleeve and roller, 20 and a piston reciprocable in the sleeve adapted to force ink from the sleeve onto said means through passages in the sleeve.

6. In an ink supply device for a typing mechanism including a writing ribbon, the combination of a container for ink having a discharge orifice through which ink is discharged for transfer to said ribbon, means for applying pressure to the ink in said container for forcing the same through said orifice for transfer to said ribbon, 30 and a porous member disposed within said container and extending across and obstructing said orifice and through which the ink under pressure is forced before leaving said orifice for controlling the discharge of ink through said orifice.

DAVID HOPPENSTAND.
